UNITED STATES PATENT OFFICE.

ELISHA B. CUTTEN, OF PITTSBURG, PA., ASSIGNOR TO THE ELECTRICAL AND MECHANICAL DEVELOPING COMPANY, OF SAME PLACE.

ARC LAMP.

SPECIFICATION forming part of Letters Patent No. 350,975, dated October 19, 1886.

Application filed April 27, 1885. Serial No. 163,562. (No model.)

To all whom it may concern:

Be it known that I, ELISHA B. CUTTEN, a resident of Pittsburg, in the county of Allegheny and State of Pennsylvania, have invented certain new and useful Improvements in Regulators for Electric-Arc Lamps, of which the following is a specification.

In electric-arc lamps as commonly made difficulty is experienced on account of the occasional sudden dropping of the upper-carbon pencil, due usually to the slipping of the clutch which engages the carbon-holding rod, or to a want of sensitiveness in the regulating mechanism, which renders its action so slow that after releasing the clutch and permitting the rod to descend it fails to effect a re-engagement until the carbon has fallen too far. This occasions sudden and violent variations in the length of the arc and a flickering and flashing of the light. A construction has been patented which seeks to overcome this difficulty by providing an additional clutch distinct from the feeding mechanism for engaging the carbon-holding rod, which clutch is connected to a retarding device—such as a dash-pot—by which it is enabled to hold the rod when the latter is released by the feeding mechanism and cause it to descend by a slow and steady movement instead of dropping suddenly. The additional clutch is lifted again in order to take a fresh hold of the rod by the movement of the solenoid, which causes the separation of the carbons.

My invention constitutes an improvement upon this construction; and it consists of certain mechanism in combination, as will be described, whereby the efficient and reliable operation of the retarding device is assured.

Figure 1 of the accompanying drawings is a front elevation, partly in section, of the regulating mechanism of an arc lamp constructed according to my present invention; and Fig. 2 is a plan thereof, partly in horizontal section, cut in the plane of the line 2 2 in Fig. 1. Fig. 3 is a diagram designed to better illustrate the operation. The remaining figures are diagrams illustrating modifications. Fig. 4 illustrates the application of my invention to an arc lamp governed by a thermo-expansion regulator; and Fig. 5 shows a modified construction applied to a solenoid-regulator.

Referring to Figs. 1, 2, and 3, let A designate the frame of the lamp; C C', the upper and lower carbon pencils, respectively; D, the rod for holding the upper carbon; F, the usual ring-clutch for engaging this rod; G and G', the solenoids or electro-magnets for effecting the lifting and feeding of the upper carbon, the solenoid-coil G being of low resistance and installed in the main circuit, and the solenoid-coil G' being of comparatively high resistance and installed in the derived circuit around the arc; and H H' the levers for communicating the movement of the solenoid-cores to the clutch F. The lever H is connected to the core of the solenoid G, and a rod, t, fixed to it, takes under one end of the clutch F, so that when the coil G is excited and draws up its core the clutch F is elevated, thus lifting the upper carbon and forming the arc. The lever H' is connected to a dash-pot, J, as usual, to prevent too sudden movement or "hammering." The lever H' is connected to the core of the solenoid G', and its free end takes over the lever H, so that when the solenoid G' is excited by an increased derived current and draws up its core the opposite end of the lever H' presses down on lever H, forcing the latter downward, and eventually releasing the clutch and allowing the rod D to descend. The adjustable springs I I', Fig. 3, are designed to counterbalance the weight of the cores.

The clutch F may be the ordinary tilting ring or washer, but I prefer the construction shown in Figs. 1 and 2, which is that claimed in my Patent No. 324,305, dated August 11, 1885. It consists of a ring, a, pivoted within an annular lever, b, one end of which is acted on by the end of the rod t, and the other end (the tail) rests on a stop-screw, c. The ring a is pivoted on an axis extending longitudinally of the lever from t to c. The tail of the lever is pressed down upon by a light spring, d, which reacts against a nut, e, screwed on a slender prolongation of the screw c. A second clutch, K, is arranged to engage the rod D, one end of its lever b being connected to the lever H', and the other end being connected to a retarding device. In this construction the retarding device is a dash-pot, L, consisting of a cylinder filled with glycerine or other

liquid, in which works a loosely-fitting piston or plunger, *p*. The stem *q* of the plunger is connected to the clutch *K* through the medium of a lever, *M*, and link *n*. The clutch *K* is connected at one end to the link *n*, and its other end or tail receives the end of a loose pin, *h*, the lower end of which is pivoted to the lever *H'*. A set-collar, *i*, on the pin *h* serves as an adjustable shoulder, which takes under the clutch *K*. A spring, *N*, connected to the lever *M*, serves to exert an upward tension on the clutch *K* and a downward pressure on the plunger *p*; or this spring may be omitted and the plunger be made heavy enough to accomplish the same result. Normally one end of the clutch *K* is elevated by the tension of the spring *N* acting through the link *n*, so that the clutch bites or engages the rod *D*. When from the lengthening of the arc the regulating mechanism releases the clutch *F*, the rod does not fall, but is suspended by the clutch *K* and link *n* from the end of the lever *M*, as shown in Fig. 3, its weight thus exerting an upward pull on the plunger of the dash-pot. The leakage of the glycerine around this plunger permits the latter to move slowly, thus causing the rod *D* and carbon *C* to descend slowly until the arc is sufficiently shortened, whereupon the regulating mechanism causes the clutch *F* to again engage the rod *D*. This is effected when the derived current has so decreased that the free end of the lever *H'* no longer presses downward upon the lever *H*, but rises therefrom, as shown in Fig. 1. In so rising it lifts the rod *b* and elevates the tail of the clutch *K*, thereby freeing the latter and enabling the spring *N* to act to elevate the opposite end of the clutch and depress the plunger, ready for the next lowering of the rod. Whenever the resistance of the arc necessitates a further feed, the downward movement of the free end of the lever *H'* first drops the tail of the clutch *K*, thus engaging this clutch with the rod, and then depresses the lever *H* and releases the clutch *F*, when the slow downward feeding of the carbon again takes place. Thus it is seen that the rod *D* is always held by one of the two clutches, neither being disengaged from it until the other has engaged with it. The clutch *K* does not interfere with the lifting of the rod, either to establish the arc or in order to insert new carbons.

The construction and operation being understood, the improvement which constitutes my invention may now be made clear. In the construction heretofore made which most nearly resembles my invention the tail-clutch *K* is connected to the core of the low-resistance solenoid *G*, (which core in that construction carries the high-resistance coil upon it,) so that when the core rises, because of the shortening of the arc, the tail of the clutch *K* is lifted and the clutch is permitted to be fed upward to take a fresh hold of the rod. With that construction the clutch *K* is lifted only when the feeding-clutch is lifted and to an ex-

tent proportional to that to which the feeding-clutch is lifted. In the ordinary working of the lamp the movement of the feeding-clutch is very slight, and consequently the clutch *K* can be lifted but a very short distance each time, and there is liability that it may at times be lifted (and thereby rendered inoperative) when the feeding-clutch is released and before the latter is lifted high enough to cause it to take hold. My invention avoids any such liability by operating the two clutches *F* and *K* independently and by separate magnets or solenoids, and by so providing giving the tail of clutch *K* a prolonged lift after the lift of the clutch, carrying with it the carbon-holding rod, has ceased. To make this action more clear, let us again follow the operation after the lowering of the upper carbon has taken place. The shortening of the arc reduces the derived current, and the core of solenoid *G'* is released and descends, thereby elevating the opposite end of lever *H'*, which ceases to press downward on lever *H*. As this end of lever *H'* rises the lever *H* rises with it until the clutch *F* takes hold of the rod *D*, when the lever *H* ceases moving. The lever *H'*, however, continues its motion and lifts the rod *h* and the tail of the clutch *K* several times higher than they would have been lifted by the motion of the lever *H* alone. Then, before another feed can take place, the lever *H'* must move back, the first effect of which is to drop the clutch *K* into engagement, and the final effect of which is to press down lever *H* until it releases clutch *F*. Thus it cannot happen that clutch *F* is disengaged before clutch *K* is brought into engagement with the rod.

Fig. 4 shows a thermo expansion regulator, being that embodied in my application for patent on electric-arc lamps executed this day. (Application No. 163,486, filed April 25, 1885.) In this regulator two thermo-expansion devices, *G* and *G'*, are substituted for the electro-magnets or solenoids in Fig. 1. The thermo device *G* consists of a series of fine wires stretched between two metal bars and receiving the main current in multiple. The thermo device *G'* consists of one, two, or more fine wires wound spirally over insulating-bars so as to form a flat coil or coils, through which the current in the derived circuit flows. As the current flowing through these thermo devices varies, they heat and cool, and consequently expand and contract, moving the levers *H* and *H'*, which levers receive the tension of springs *I* and *I'* in such direction that they tend to stretch the wires *G* and *G'*, and the two springs pull against each other when the levers are in contact. When the thermo device *G* is heated and relaxes, the spring *I* lifts the clutch *F* and rod *D*. When *G'* is heated and relaxes, the spring *I'* presses in the opposite direction, overcomes the effective tension of spring *I*, and releases the clutch, permitting the rod to descend. There is no need of the usual dash-pot, *J*, Fig. 1, as the

movements of the thermo devices G G' are positive and free from momentum; but there is with this regulating mechanism, as with others, a liability that the carbon may fall too far, and to prevent this I apply the second clutch, K, and its lifting and retarding devices. Their construction is substantially the same as in the form first described. When the free end of the lever H' moves down, it drops the tail of clutch K, and permits it to engage the rod before it depresses lever H' enough to disengage clutch F. On rising it lifts the tail of clutch K a considerable distance and permits spring N to draw up the clutch and press down the plunger p in the dash-pot cylinder. This movement of the plunger is facilitated by its being constructed with cupped packing, as shown, which yields as it moves downward, but swells outwardly as it is pulled upward by the descent of the carbon. In this instance it is sufficient if the dash-pot contain only air instead of liquid.

In Fig. 5 I have shown another form of solenoid-regulating mechanism, to which is applied a modified construction of my invention. The cores of the solenoids G and G' are connected to opposite ends of a walking-beam or lever, H, the former by being jointed to it and the latter by having a toe, u, which takes over the end of the lever and bears down upon the latter when the core is drawn downward by the attraction of the coil. A spring, I', is arranged to pull upwardly on the core of G', and lifts its toe u above the lever H, except when the current in the derived circuit is sufficient to cause the solenoid G' to draw the core down. A lever, H', is jointed to the stem of the core, and its free end, which rises and falls with the movement of the core, carries a pendent link, h, the lower end of which takes under the tail of the clutch K. The other end of this clutch is connected by a rod, n, with a ratchet-rack, r, which is drawn upward by a spring, I, which thus tends to lift the clutch K. The inclined teeth of the ratchet-rack / mesh with the similar teeth of a ratchet-wheel, m, and are kept in mesh with the latter by a spring, s, which presses the rack toward the wheel, but which yields when the rack is moving upward and permits it to freely pass the teeth of the ratchet-wheel. This wheel is fixed on the same arbor with a gear, M', which meshes with a pinion, I, and on the arbor of this pinion is fixed a fan or flier, L. This constitutes the retarding device. When the rod D is released by the clutch F, it hangs suspended from the clutch K, and its weight comes upon the rack r, overcoming the spring I. The rack, being in engagement with the ratchet-wheel m, rotates the latter, and consequently revolves the fan L, which retards the movement and causes the carbon to be lowered with a slow and even motion until its descent is interrupted by the re-engagement of the clutch F. This re-en-

gagement occurs only when the solenoid G' has released its core and the toe u has ceased to press down upon the lever H'. The upward movement of the core raises the lever H' and frees the clutch K, which is elevated again by the spring I and takes a new hold of the rod higher up.

I claim as my invention—

1. In an electric-arc lamp, the combination of the carbon-holding rod, the feeding-clutch engaging said rod, a solenoid or equivalent electro-motive device in the main circuit connected to said clutch and adapted to lift said clutch and rod, a solenoid or equivalent electro-motive device in the derived circuit, its mobile member having a movement independent of that in the main circuit, and adapted when excited by a derived current to exert a pressure tending to release said feeding-clutch, a second clutch engaging said rod, a retarding device connected to said second clutch and adapted to retard its descent, and connection between the mobile element of said derived-circuit electro-motive device and said second clutch, substantially as set forth, whereby on the diminution of the derived current said mobile element after ceasing to act on the feeding-clutch takes under the tail of the second clutch and feeds it upward.

2. In an electric-arc lamp, the combination of carbon-holding rod D, feeding-clutch F, lever H, operating said clutch, a second clutch, K, engaging said rod, a retarding device to retard the descent of clutch K, a lever, H', adapted when depressed to bear down on lever H to tend to release clutch F, and when elevated to rise free from lever H and lift the tail of clutch K, thereby feeding the latter upward, and electro-motive devices in the main and derived circuits, respectively, with their mobile elements connected, respectively, to levers H and H', substantially as set forth.

3. In an electric-arc lamp, the combination of the carbon-holding rod D, the feeding-clutch F, the lever H, controlling it, the solenoid G or equivalent electro-motive device in the main circuit, with its mobile element connected to said lever, the lever H', adapted to bear down against lever H or to rise free therefrom, the solenoid G' or equivalent electro-motive device in the derived circuit, with its mobile element connected to said lever H', the clutch K, a spring tending to lift said clutch, a retarding device adapted to retard the descent of said clutch, and a vertically-adjustable connection between the lever H' and the tail of said clutch, substantially as set forth.

In witness whereof I have hereunto signed my name in the presence of two subscribing witnesses.

ELISHA B. CUTTEN.
